SHELF

William E. Mell, Chicago, Ill., assignor to Mell-Hoffmann Mfg. Co., Chicago, Ill., a corporation of Delaware

Application February 11, 1949, Serial No. 810

Term of patent 7 years

(Cl. D33—3)

To all whom it may concern:

Be it known that I, William E. Mell, a citizen of the United States, residing at Chicago, Cook County, Illinois, have invented a new, original, and ornamental Design for Shelf, of which the following is a specification, reference being had to the accompanying drawing, forming a part thereof.

Fig. 1 is a perspective view of the shelf; Fig. 2 illustrates an end view of the shelf; and Fig. 3 is a top view of the shelf.

I claim:

The ornamental design for a shelf, substantially as shown.

WILLIAM E. MELL.
